UNITED STATES PATENT OFFICE.

CECIL O. PHILLIPS, OF NEW YORK, N. Y.; ELIZABETH L. PHILLIPS EXECUTRIX OF
SAID CECIL O. PHILLIPS, DECEASED.

CONTAINER FOR POWDERS.

Application filed June 6, 1922. Serial No. 566,381.

To all whom it may concern:

Be it known that I, CECIL O. PHILLIPS, a citizen of the United States, residing at New York, in the county of New York, State of New York, have invented certain new and useful Improvements in Containers for Powders; and I do hereby declare the following to be a full, clear, and exact description of the invention, such as will enable others skilled in the art to which it app pertains to make and use the same.

This invention relates to improvements in containers for powders, granules, flakes, etc., and more particularly to sanitary containers comprising an outer container member or casing and inner or refill cartons adapted to be inserted and contained therein, the outer container and inner carton being of such shape, size and configuration that the carton can be readily inserted in the outer casing, and the outer casing being provided with means for perforating the inner carton when inserted therein.

The improved containers of the present invention are adapted for use with materials in powdered or similar form, for example, with talcum powders, soap powders, granules or flakes of soap and similar materials which are packaged in powder or similar form and intended for use in small amounts, for example, by shaking the powder from the container.

The invention will be further described in connection with the embodiments thereof illustrated in the accompanying drawings, but it is intended and will be understood that the invention is illustrated by, but is not limited to, the specific construction thus illustrated and described.

In the accompanying drawings Fig. 1 shows a preferred embodiment of the invention in central section.

Fig. 2 is a section on line 2-2 of Fig. 1.

Fig. 3 is a bottom view of the container of Fig. 1.

Fig. 4 is a side view of one form of the container bottom separated from the container.

Fig. 5 is a detailed view showing a modified construction of part of the container.

Fig. 6 is a partial sectional view showing the bottom of a container of modified construction.

Figs. 7 and 8 are respectively side and

top views of one form of inner carton or refill carton.

Fig. 9 is a partial section view showing the top of a container of modified construction.

Fig. 10 is a side view of a modified form of carton.

Figs. 11 and 12 are respectively top and side views of one form of cone similar to that illustrated in Fig. 1, and

Figs. 13 and 14 are respectively top and side views of a closed cone such as is illustrated at the bottom of the container of Fig. 1.

One form of the container, comprising the outer member and the inner refill member, is illustrated in Fig. 1. The outer casing 1 may be of any suitable shape, such as round, square, oval, etc., but is shown round for convenience of illustration.

The upper part of the casing is formed as a single member, for example, by spinning, drawing, stamping, etc., and is provided with a neck 2 and perforations 3 as well as holes 4 outside the neck 2. At its lower end the casing has a bottom closure 6 which telescopes into the lower end of the casing 1 with a close fit. The bottom member 6 has an outer rim or flange 7 which spaces the container away from the table or article on which it stands. The bottom member also has openings 8 best shown in Fig. 3. The telescoping portion 6 may be split as indicated at 9 in Fig. 4 to give a wedging fit and prevent accidental removal of the bottom member from the casing, or the bottom member may be locked in place by projections or beads such as those indicated at 10 in Fig. 5, the projection on the bottom member 6 snapping into a recess in the casing member 1 and preventing accidental removal of the bottom member except when sufficient force is applied.

A cover member 11 is shown at the top of the container, this cover member being removable and having a wedge fit.

The inner cartons or refills are illustrated in Figs. 7-10. These may be of cylindrical or other shape corresponding to that of the outer casing, and they are preferably of a material readily perforable or with special portions which are readily perforable. These inserts or refills may, for example, be made of waterproof cardboard or paper such that they will protect their contents from

atmospheric conditions and from the accidental introduction of moisture. At both ends of these inner cartons 12 there are provided weakened portions or readily perforable portions 13 which may be made by making a hole in the cardboard and closing it with a thin paper layer or by partially cutting through the cardboard so that the carton is easily perforated at the partially cut portions. In Fig. 8 the central portion 13 is square; however, it may be round, the particular shape being immaterial.

Projecting downwardly from the under side of the top of the outer casing 1, as shown in Fig. 1, is an open cone 15 in the shape of a pyramid. This pyramid is so arranged that when a fresh carton or refill is inserted in the outer casing the cone will project into the carton, thereby opening the carton so that its contents can pass out through the open cone to the neck of the container and thence through the holes 3. If the refills 12 have openings in the container which are covered by thin paper, the cone 15 of Fig. 1 will perforate the paper, thus opening communication between the inside of the carton and the neck of the container.

The carton 12 shown in Fig. 9 is provided with a neck 18 at the top thereof. The shape of this carton is, therefore, similar to the shape of the outer casing 1. The top of the neck 18 may be made of perforable material, or it may have a suitable cap which may be removed before the carton is inserted in the outer casing.

The bottom 6 of the outer casing may or may not have a cone or other perforating means. In Fig. 1 a cone 16 is shown, while in Fig. 6 the bottom member 6 is flat and has no such cone. If the bottom member 6 is provided with a cone such as that of Fig. 1, the cone is preferably closed so that, although the inner carton is perforated, the cone will nevertheless close the opening.

If the bottom of the outer container has no cone or projection, the inner carton or refill member will not be perforated at the bottom so that the contents will be kept in a protected condition and leakage of water into the bottom of the carton will be prevented.

The holes 4 and 8 shown in Figs. 1-3 will be closed by the ends of the inserted carton so that there will be no opportunity for escape of the contents of the carton therethrough. These openings will nevertheless permit access to be had to the carton and facilitate its removal from the outer casing, while they also serve to give to the container a distinctive appearance.

The conical members or other perforated members may be of different shape and construction. One form of open cone for perforating the tops of the cartons is illus-

trated in Figs. 11 and 12. The construction of the closed cone 16 of Fig. 1 is further shown in Figs. 13 and 14.

The carton itself may vary in its construction and in the material of which it is made, but it should either be made of perforable material or should be provided with portions of perforable material, for example, made by cutting away a part of the material and closing it with thin material, or by cutting away all the material of the ends of the carton. The cartons may also have depressions into which the cones or projections may fit, and certain of the projections or depressions may be so constructed as to permit access to the inside of the cartons, for example, to permit the escape of the contents of the carton. One such depression is shown in Fig. 10 at 17.

In using the carton, the insert or refill member will be introduced into the outer casing by removing the outer member 6, and the inserted member will be forced up against the cone 15 which will perforate the upper end and establish communication between the inside of the carton and the neck of the container. By then placing the bottom member 6 in place, the carton will be held securely against the ends of the outer member and the entire box or container can be handled as a whole so that the powder or other contents of the container can be shaken out in much the same manner as talcum powder is shaken from an ordinary talcum powder box.

It is one objection to the ordinary talcum powder box that the box itself, usually of metal and often decorated, is itself an expensive element, and may be much more expensive than the talcum powder which it contains. The composite container of the present invention enables the same outer container to be used, and this container itself may be expensive in character or relatively more expensive than the material to be dispensed from it. It may be of gold or silver, or it may be ornamented in various ways. By supplying cartons or refills of suitable shape and size, they can be used with the same outer casing so that when one carton is empty another can be inserted. The cartons themselves may be of inexpensive material, thus materially reducing the total cost of the talcum powder or similar material, while nevertheless making it available in much the same manner that it is available in ordinary metal containers.

The composite containers of the present invention are also of special advantage for use in dispensing soap. By providing the soap in powder form or in flake form, or in granules, in a water proof container, the soap will be preserved in the desired state until used. These containers can be inserted in the outer metal container and the inner

container or carton will be perforated and the soap contents thus made available. Soap powder can thus be handled in much the same manner that talcum powder is handled. That is, the soap can be shaken from the container as desired, and the soap which is not used will remain protected. Soap containers of this kind are sanitary, and the soap is protected from contamination or from being moistened, until it is shaken from the container for use.

By making the insert cartons or refills with both ends perforable, they are interchangeable end for end and either end can be inserted into the outer container. The outer container itself need not be imperforate, for the contents of the inner carton are prevented from escaping except at the perforated portions where escape is desired.

It will thus be seen that the present invention provides an improved container having many advantages, and in particular that it provides a container having an outer casing of a relatively permanent character adapted for continued use over long periods of time, together with an inner carton or refill which is itself inexpensive in construction and readily inserted and renewed. The cartons themselves can thus be provided in any desired number for use with a single outside container and the cartons when empty can be readily removed from the container and a new carton substituted.

It will be evident that variations and modifications may be made in the construction of the containers without departing

from the spirit and scope of the invention as defined in the appended claims.

I claim:

1. In a composite container for powders and the like, an outer casing adapted to receive a refill carton having one end thereof perforable, said outer casing having one end thereof removable, and having an opening for the escape of the material within the refill carton, and an angular cage-like perforating member for perforating the carton adjacent said opening. 40

2. In a composite container for powders and the like, an outer metal casing adapted to receive a refill carton having one end thereof perforable, said outer casing having a removable bottom and a perforated neck at its top, adapted to dispense powdered material, and an inwardly-converging pointed cage-like perforating device carried by said casing, adjacent said neck for perforating the carton. 50

3. In a composite container for powders and the like, an outer casing adapted to receive a refill carton and having perforations therein, certain of said perforations being adapted to be closed by the refill carton and to be used in forcing out the carton when empty, and means for perforating the carton to permit the contents thereof to escape through the remaining perforations in the outer casing. 65

In testimony whereof I affix my signature.

CECIL O. PHILLIPS.
